BICYCLE

Sherwood B. Ross, Woodsburgh, N.Y., assignor to Chain
Bike Corporation, Rockaway Beach, N.Y., a corporation of New York

Filed June 1, 1964, Ser. No. 80,216

Term of patent 14 years

(Cl. D90—8)

The figure is a perspective view of a bicycle, showing my new design.

The dominant features of the design reside in the portions shown in full lines.

I claim:

The ornamental design for a bicycle, substantially as shown and described.
